No. 634,634.

Patented Oct. 10, 1899.

R. G. WHITLOCK.
AUTOMATIC MEASURING DEVICE.

(Application filed Nov. 17, 1898.)

(No Model.)

Fig. 3.

UNITED STATES PATENT OFFICE.

RALPH G. WHITLOCK, OF DES MOINES, IOWA, ASSIGNOR TO E. D. WHITLOCK, OF LOS ANGELES, CALIFORNIA.

AUTOMATIC MEASURING DEVICE.

SPECIFICATION forming part of Letters Patent No. 634,634, dated October 10, 1899.

Application filed November 17, 1898. Serial No. 696,745. (No model.)

To all whom it may concern:

Be it known that I, RALPH G. WHITLOCK, a citizen of the United States, residing at Des Moines, in the county of Polk and State of Iowa, have invented a new and useful Automatic Measuring Device, of which the following is a specification.

The object of this invention is to provide a cabinet of simple, strong, durable, and inexpensive construction in which a number of different kinds of granular substances may be stored and uniform given quantities of such substances be quickly and easily taken therefrom.

15 My object is further and more specifically to provide mechanism of improved and simplified construction for measuring the substances and discharging same.

20 My invention consists, essentially, in the details of construction of the valves and their operating means and in the combination thereof in the cabinet, as hereinafter more fully set forth, pointed out in my claims, and illustrated in the accompanying drawings, in

25 which—

Figure 1 shows a side elevation of one of the complete measuring devices detached from the cabinet and with parts broken away to show certain details of construction. Fig. 30 2 shows a plan view of one of the valves, and Fig. 3 shows a perspective view of the cabinet with one corner of the casing broken away to show the arrangement of the measuring devices therein.

35 Referring to the accompanying drawings, I have used the reference-numeral 10 to indicate the frame of the cabinet, which is divided into compartments by the partitions 11. In the top of each compartment is a hopper 40 12, in which the substance is stored. At its front is a hinged door 13, which may be opened to provide access to the measuring devices, and the front is open at its bottom to provide access to the measured substances.

45 At the bottom of each of the hoppers is a tube 14, which is preferably square in cross-section, open at its top and bottom and having the openings 15 in its front and back sides near its top and the like openings 16 in its lower end portion. A tube-section 17, also 50 square transversely, is telescoped over the up-

per end of the tube 14 and has narrow horizontal slots at its front and back, the vertical slots 18 at its sides, and the tracks or guides 20 at its sides below the slots 18. A 55 screw-bolt 21 extends through the solid sides of the tube 14 and through the slots 18, thus providing for the vertical adjustment of the tube 17 on the tube 14. A tube 23 of identical construction is mounted on the lower 60 end of the tube 17. The upper valve is composed of a rectangular metal frame 23, having the inner edges of its side pieces designed to enter the tracks or guides 20 and be capable of sliding longitudinally therein. In the 65 outer edges of said side pieces, near the forward end thereof, are the notches 24. In the central portion of the frame is the valve proper, 25, attached to the said frame at its front and back only, with a space between its 70 edges and the side of the frame and having the rear end thereof cut away, save for a central supporting-piece, for about one-third of its length.

Mounted in the lower tube-section 22 is a 75 valve of identical construction provided with a handle 26 to project forwardly therefrom.

At the central portion of the tube 14 is a frame 27, having at its forward corners the journals 28, upon which the levers 29 are fulcrumed. Said levers have tapered ends which enter the notches 24 in both valves, which valves are so arranged that when one is at its forward limit the other is at its rearward extreme.

85 In practical use and assuming that the device were in the position shown in Fig. 1 it is obvious that the contents of the hopper would fill the entire tube 14 as far as the lower valve. When it is desired to measure out a 90 quantity of the substance, the handle 26 is pulled. This has the effect of drawing the lower valve forwardly and, by reason of the levers 29, forcing the upper valve rearwardly. The said upper valve is of such size as to 95 close the opening through the tube 14 before the opening in the lower valve comes into the tube 14, thus shutting off the upper end of the measurer. Then as the handle 26 is drawn further the opening in the lower valve permits the measured substance in the tube to 100 pass out through the bottom of the tube.

Then as the handle is again pushed back the lower valve closes the tube before the upper valve is opened. When said upper valve is finally opened, the tube 14 is filled again. By 5 reason of the openings in the front and back of the tube 14 the valves may be adjusted upon the tube and freely operate at any point within the limit of the said openings. This 10 adjustment is had by means of the screw-bolts at the sides of the movable tube-sections.

Having thus described my invention, what I claim as new therein, and desire to secure by Letters Patent of the United States therefor, 15 is—

1. In an automatic measuring device, an open-ended four-sided tube, tracks on the outside faces of two of the parallel sides of the tube, slots across the other two sides of 20 the tube in the plane of the tracks, a frame fitted to slide on said tracks and a valve fixed to the frame to slide through said slots in the manner set forth for the purposes stated.

2. In an automatic measuring device, a 25 quadrangular frame, having notches in its parallel sides for slidingly connecting levers therewith, a float-valve fitted in the frame and fastened to the ends of the frame in such a manner as to leave narrow spaces between 30 its side edges and the parallel side bars of the frame, in combination with an open-ended four-sided tube having tracks on two parallel sides to support said frame and valve and transverse slots in its other two parallel sides 35 for the passage of the valve fixed to the frame

and levers to enter the notches in the frame, all arranged and combined to operate in the manner set forth for the purposes stated.

3. An automatic measuring device, comprising a tube having horizontal openings at 40 its front and back at each end guides or tracks fixed to the outer surfaces of the sides of the tube adjacent to said openings, a valve at each end, each valve comprising a frame mounted for movement in said track, and a 45 valve proper fixed in each frame to pass through said openings and having a part at its rear end open, and levers fulcrumed to the central portion of the tube and slidingly connected with each of said frames carrying 50 fixed valves to operate in the manner set forth for the purposes stated.

4. An automatic measuring device, comprising in combination, an open-ended tube rectangular in cross-section, and having openings in its front and back near its top and bottom tube-sections adjustably telescoped to said ends and having narrow slots in their front and back faces, tracks or guides at their sides, rectangular frames mounted in said 60 guides and having notches therein, a handle attached to one of the frames, a valve in each frame open at its rear end and two levers fulcrumed to the central portions of the tube with their ends in said notches substantially 65 as and for the purposes stated.

RALPH G. WHITLOCK.
